(57) **CLAIM**

The ornamental design for an individual thin brick, as shown and described.

DESCRIPTION

FIG. 1 is a perspective view of a first embodiment of an individual thin brick showing my new design;
FIG. 2 is a front elevational view of the first embodiment of the claimed individual thin brick;
FIG. 3 is a bottom elevational view of FIG. 2;
FIG. 4 is a left side elevational view of FIG. 2;
FIG. 5 is a right side elevational view of FIG. 2;
FIG. 6 is a rear elevational view of FIG. 2;
FIG. 7 is a top elevational view of FIG. 6;
FIG. 8 is a perspective view of a second embodiment of an individual thin brick showing my new design;
FIG. 9 is a front elevational view of the second embodiment of the claimed individual thin brick;
FIG. 10 is a bottom elevational view of FIG. 9;
FIG. 11 is a left side elevational view of FIG. 9;
FIG. 12 is a right side elevational view of FIG. 9;
FIG. 13 is a rear elevational view of FIG. 9; and,
FIG. 14 is a top elevational view of FIG. 9.
The broken lines in the Figures are for illustrative purposes only and form no part of the claimed design.
